UNITED STATES PATENT OFFICE.

JOHN F. FIERKE, OF DUNDEE, ILLINOIS, ASSIGNOR TO ILLINOIS IRON & BOLT COMPANY, OF CARPENTERSVILLE, ILLINOIS, A CORPORATION OF ILLINOIS.

TRUCK.

939,406.

Specification of Letters Patent.

Patented Nov. 9, 1909.

Application filed June 15, 1909. Serial No. 502,279.

To all whom it may concern:

Be it known that I, JOHN F. FIERKE, a citizen of the United States, residing at Dundee, in the county of Kane and State of Illinois, have invented certain new and useful Improvements in Trucks, of which the following is a specification.

My invention relates to a metal truck and has for its object certain new and useful improvements in the construction of trucks of this sort, whereby a truck is provided which shall be light, strong, economical to manufacture, and constructed in such a way that it may be easily taken apart to replace 15 or repair broken or otherwise injured parts.

The invention has for one of its objects, to be more specific, to provide a frame for a truck consisting of parts which may be made of relatively thin pressed steel but so 20 formed and secured together as to combine strength with lightness.

Another object of the invention is to provide a truck, otherwise made of metal, which shall have wooden handles, and further, to provide effective means for securing the wooden handles to the metal frame in such a way that they may be easily removed and replaced when broken.

The invention has for further objects such 30 other improvements in the construction of steel trucks as will be described in this specification and set forth in the claims appended thereto.

A preferred construction of truck made in 35 accordance with my invention is shown in the accompanying drawings, in which—

Figure 1 is a longitudinal sectional view through the truck. Fig. 2 is an inverted plan view of the same. Fig. 3 an enlarged 40 view in perspective, illustrating the construction of one of the legs and the parts associated therewith. Fig. 4 shows a sheet of metal as it is stamped out to form one of the channel bar cross pieces. Fig. 5 shows 45 the same part when it has been finished. Fig. 6 is a view in perspective of one of the side pieces of the truck frame. Fig. 7 is a section taken on line 7—7 of Fig. 1 looking in the direction of the arrows.

Like characters of reference indicate like 50 parts in the several figures of the drawings.

Referring to the drawings, 10—10 represent the side pieces which are preferably made of relatively thin pressed steel bent 55 to form angle bars. In order to give addi-

tional strength the depending flanges 11 of the sills are in truss form, as shown, being wider at the center than at the ends. These sills are connected together at suitable intervals by cross pieces 12, preferably formed 60 also of relatively thin pressed steel. These cross pieces may be stamped out from sheets of metal in the form shown in Fig. 4, and afterward bent so as to form channel bars of the character shown in Fig. 5. These parts are made with the lugs 13 which are bent down as shown in Fig. 5, affording 65 means for securing the cross pieces to the flanges 11 of the sills. The sills may be connected at the forward end by the angle bar 14. Longitudinal metal strips 15, 15 are 70 secured to the cross pieces.

The wheels 16, 16 are connected by the axle 17 which turns in bearings in the metal brackets 19, 19, which are bolted to the sills 75 and preferably abut against the angle bar 14.

A nose 20 may be bolted to the sills by the same bolts 21, which secure the brackets and angle iron to the sill.

It has been found undesirable to construct 80 metal trucks with hand grips of metal as metal is very cold to the touch and moreover is very likely to become bent unless made strong and heavy. I provide my truck with the wooden handles 22, 22 having the 85 squared ends 23, 23 which lie within the angles of the sills, and preferably abut against the rearmost cross piece 12. The handles are secured to the sills by the vertical bolts 24 and the horizontal bolts 25. 90

The legs preferably consist of the V-shaped strips of steel 26 riveted at one end to the sills and at the other end provided with the horizontal parts 27 which lie along the under side of the squared ends of the handles. 95 The rear bolts 24 secure the legs to the handles and the sills. Preferably, the legs are braced by the transverse metal strip 28 riveted to the V-shaped pieces and provided at the upper end with the horizontal part 29 100 which seats within the rear channel member 12, being preferably riveted thereto.

It has been customary in warehouse 105 trucks to make the handle and the sill on each side of the truck of one piece of wood. But it is objectionable because when the handles break, which happens quite frequently, the whole truck has to be taken to pieces in order to replace them. It will be seen that in the truck as above described, 110

the handles may be removed by simply taking out bolts 24 and 25. The handles are, nevertheless, held firmly in position, being engaged above and at one side by the sill, 5 on the under side by the legs, and at the ends abutting against the rearmost cross piece.

By constructing the frame of relatively thin pressed steel angle bars of truss form as shown and the cross pieces of relatively 10 thin pressed steel in the form of channel bars, the frame of the truck can be made very light without sacrificing strength. A very serious objection to the old metal trucks which have heretofore been made, has been that, though strong, they are altogether 15 too heavy. The truck of my invention is hardly heavier than the ordinary wooden truck and at the same time is very much stronger. By making the transverse braces 20 for the legs of one strip of metal the horizontal portion 29 of which extends through the rearmost cross piece, the latter is reinforced; and it is, ordinarily, upon this cross piece that the greatest strain comes.

25 I do not limit myself to the exact devices, constructions and arrangements shown and described, as modifications might be devised which would come within the scope of my invention as defined by the claims.

30 I claim:

1. In a truck, the combination with metal angle bar sills, of metal cross pieces connecting said sills, wooden handles having ends square in cross section, which are set 35 into the angles of the sills, bolts for securing the handles to the sill, supporting wheels for said frame, and legs comprising V-shaped strips of metal secured at one end to the sills and at the other secured to the under sides 40 of said handles.

2. In a truck, the combination with angle bar sills, metal cross pieces connecting said sills, wooden handles having ends square in cross section, set into the angles of the sills, 45 legs comprising strips of metal secured at one end to the sills and at the other extending along the under side of said handles, and

bolts securing the handles to the vertical flanges of the sills, and securing the handles to the horizontal parts of the sills and to 50 said metal strips forming the legs.

3. In a truck, the combination with angle bar sills, of channel bar cross pieces, wooden handles provided with ends square in cross section which are set into the angles 55 of the sills and abut the rearmost of said cross pieces, legs comprising V-shaped strips of metal secured to the sills, bolts securing said handles to said sills and to the legs, and braces for the legs comprising a strip of 60 metal riveted to the V-shaped strips and set into and riveted to the rearmost cross piece.

4. In a truck, the combination with pressed steel angle bar sills of truss form, of pressed steel channel bar cross pieces provided at their ends with lugs adapted to be riveted to said sills, wooden handles having squared ends seated in the angles of the sills and abutting against the rearmost cross piece, legs comprising strips of metal secured at one end to the sills, and at the other 65 extending under the handles, bolts securing the handles to the sills and to the legs, braces for the legs comprising a strip of metal riveted to the V-shaped strips and set into 70 and riveted to the rearmost cross piece, and wheels at the forward end of said truck.

5. In a truck, the combination with angle bar sills, of channel bar cross pieces, wooden handles provided with ends square in cross 80 section, which are set into the angles of the sills and abut the rearmost of said cross pieces, legs comprising V-shaped strips of metal secured to the sills, bolts securing said handles to said sills and to the legs, and a 85 single transverse brace for both legs, consisting of a strip of metal riveted at each end to the V-shaped strips and extending through channel of and riveted to the rear-most cross piece.

JOHN F. FIERKE.

12/65 10 AM. 10 Trucks
tion in Letters Patent No. 939,406

It is hereby certified that in Letters Patent No. 939,406, granted November 9, 1909, upon the application of John F. Fierke, of Dundee, Illinois, for an improvement in "Trucks," an error appears in the printed specification requiring correction, as follows: Page 1, line 93, the word "tills" should read *sills*; and that the said Letters Patent should be read with this correction therein that the same may conform to the record of the case in the Patent Office.

Signed and sealed this 80th day of November, A. D., 1909.

[SEAL.]

E. B. MOORE,

Commissioner of Patents.

the handles may be removed by simply taking out bolts 24 and 25. The handles are, nevertheless, held firmly in position, being engaged above and at one side by the sill, 5 on the under side by the legs, and at the ends abutting against the rearmost cross piece.

By constructing the frame of relatively thin pressed steel angle bars of truss form as shown and the cross pieces of relatively 10 thin pressed steel in the form of channel bars, the frame of the truck can be made very light without sacrificing strength. A very serious objection to the old metal trucks which have heretofore been made, has been that, though strong, they are altogether 15 too heavy. The truck of my invention is hardly heavier than the ordinary wooden truck and at the same time is very much stronger. By making the transverse braces 20 for the legs of one strip of metal the horizontal portion 29 of which extends through the rearmost cross piece, the latter is reinforced; and it is, ordinarily, upon this cross piece that the greatest strain comes.

25 I do not limit myself to the exact devices, constructions and arrangements shown and described, as modifications might be devised which would come within the scope of my invention as defined by the claims.

30 I claim:

1. In a truck, the combination with metal angle bar sills, of metal cross pieces connecting said sills, wooden handles having ends square in cross section, which are set 35 into the angles of the sills, bolts for securing the handles to the sill, supporting wheels for said frame, and legs comprising V-shaped strips of metal secured at one end to the sills and at the other secured to the under sides 40 of said handles.

2. In a truck, the combination with angle bar sills, metal cross pieces connecting said sills, wooden handles having ends square in cross section, set into the angles of the sills, 45 legs comprising strips of metal secured at one end to the sills and at the other extending along the under side of said handles, and

bolts securing the handles to the vertical flanges of the sills, and securing the handles to the horizontal parts of the sills and to 50 said metal strips forming the legs.

3. In a truck, the combination with angle bar sills, of channel bar cross pieces, wooden handles provided with ends square in cross section which are set into the angles 55 of the sills and abut the rearmost of said cross pieces, legs comprising V-shaped strips of metal secured to the sills, bolts securing said handles to said sills and to the legs, and braces for the legs comprising a strip of 60 metal riveted to the V-shaped strips and set into and riveted to the rearmost cross piece.

4. In a truck, the combination with pressed steel angle bar sills of truss form, of pressed steel channel bar cross pieces provided at their ends with lugs adapted to be riveted to said sills, wooden handles having squared ends seated in the angles of the sills and abutting against the rearmost cross piece, legs comprising strips of metal secured at one end to the sills, and at the other 65 extending under the handles, bolts securing the handles to the sills and to the legs, braces for the legs comprising a strip of metal riveted to the V-shaped strips and set into 70 and riveted to the rearmost cross piece, and wheels at the forward end of said truck.

5. In a truck, the combination with angle bar sills, of channel bar cross pieces, wooden handles provided with ends square in cross 80 section, which are set into the angles of the sills and abut the rearmost of said cross pieces, legs comprising V-shaped strips of metal secured to the sills, bolts securing said handles to said sills and to the legs, and a 85 single transverse brace for both legs, consisting of a strip of metal riveted at each end to the V-shaped strips and extending through channel of and riveted to the rear-most cross piece.
